(57) **CLAIM**

The ornamental design for a table, as shown and described.

DESCRIPTION

FIG. 1 is a front elevational view of a table showing my new design;

FIG. 2 is a rear elevational view thereof;

FIG. 3 is a left side view thereof;

FIG. 4 is a right side view thereof;

FIG. 5 is a top plan view thereof;

FIG. 6 is a front perspective view thereof;

FIG. 7 is a front perspective view thereof, shown in an alternate environment where the table top is transparent;

FIG. 8 is right side perspective view of FIG. 7; and,

FIG. 9 is left side perspective view of FIG. 7.

The broken lines illustrate portions of the table that do not form part of the claimed design.
